C. P. BARTELS

FIREPROOF SAFE DOOR

Filed Sept. 26, 1924

INVENTOR

Carl P. Bartels
BY
J. Edwards
ATTORNEY

UNITED STATES PATENT OFFICE.

CARL P. BARTELS, OF HAMILTON, OHIO, ASSIGNOR TO THE MOSLER SAFE COMPANY, OF HAMILTON, OHIO, A CORPORATION OF NEW YORK.

FIREPROOF SAFE DOOR.

Application filed September 26, 1924. Serial No. 740,000.

To all whom it may concern:

Be it known that I, CARL P. BARTELS, a citizen of the United States, residing at Hamilton, in the county of Butler and State 5 of Ohio, have invented certain new and useful Improvements in Fireproof Safe Doors, of which the following is a specification.

This invention relates to safe doors, and the principal aim of the invention is to provide means for establishing a fireproof seal 10 across the dooway when the safe is subjected to a fire hazard to prevent entrance of heat, flame, smoke, and steam, or the like, into the interior of the safe, and thus protect the contents of the safe from damage 15 and injury by these elements.

Another object of this invention is to provide simple means for holding an auxiliary or valve door portion in place on a main 20 door portion in such a way that the valve door will be released automatically from the main door at a comparatively low temperature, and will become seated against cooperating jamb shoulders to form an effective 25 fireproof seal across the doorway, said means under normal conditions, however, holding the valve door securely in proper position on the main door.

A further object of this invention is to 30 simplify the construction and to reduce the cost of manufacture, and to secure a very light construction.

Other objects of this invention will be in 35 part obvious and in part pointed out hereinafter.

In accordance with this invention, the valve door is secured to the main door by means which include solder, or other suitable material which melts or fuses at comparatively low temperature, the effectiveness of the means being depending upon the condition of the solder in such a way that when the solder is hard, as under normal 40 temperature conditions, the valve door is held to the main door in proper position, and when the solder is fused, as under abnormally high temperature conditions, the valve door can be displaced from the main door. There also are means which cause 45 the valve door to seat firmly against shoulders on the safe jamb to establish and to maintain an effective fireproof seal, in the manner of a valve, when the valve door

is freed from the main door in consequence of the melting of the solder, and irrespective 55 of warping of the main door.

This invention accordingly consists in the features of construction, combinations of elements and arrangement of parts which will be exemplified in the construction hereinafter set forth and the scope of the application of which will be indicated in the following claims.

In order that a clearer understanding of my invention may be had, attention is hereby directed to the accompanying drawings forming a part of this application and illustrating certain possible embodiments of my invention. Referring to the drawings, Fig. 1 is a sectional view of a safe door embodying this invention, associated with the jamb portion of a safe, the middle of the door being broken away; and Figs. 2, 3, 4 and 5 are each a sectional view of a fragment of the door showing a different 75 modified form of stud for holding the valve door on the main door.

Similar reference characters refer to similar parts throughout the several views of 80 the drawings.

Referring to the drawings, the door comprises a main door 1 and a valve door 2 secured to the main door by means of a suitable number of studs 3, which engage both doors. As shown, each stud 3 has a 85 shank 4 extending through the valve door, with a head 5 on one side of the valve door and a threaded end 6, engaged in a threaded perforation or recess 7 in the back plate 8 of the main door. The doors 1 and 2 are held normally some distance apart, as determined by the length of shank 4 with respect to the thickness of the valve door, by means of plate springs 9, which are interposed between the doors, and which may be held against displacement by being penetrated by the studs 3. The valve door is 90 slidable on the stud shanks 4 against the pressure of springs 9. The safe jamb 10 is provided with shoulders 11 against which the valve door 2 is adapted to seat to close the doorway of the safe, and the valve door may be arranged to seat against these shoulders and against resilient pressure of 100 the springs 9 whenever the door is closed. 105 By constructing the studs 3 of two parts

held together by solder, or material which fuses at a comparatively low temperature, I am able to have the valve door become released automatically from the main door and 5 to become seated firmly against the jamb shoulders 11, in the manner of a valve, by the action of springs 9, whenever the solder lets go, which it will do quite quickly when a fire hazard arises. To this end the studs 10 may be constructed in various forms, some of which are shown in Figs. 2, 3, 4 and 5 of the drawings, and the construction of which will now be described.

As shown in Fig. 2, the stud 12 may comprise a pin 13 threaded into the head 14 and seating within a recess 15 in the shank 16 which is in threaded engagements with the back plate 8 of the door 1, there being solder 17 in the recess 15 which secures the pin 13 and shank 16 together until the solder melts, in which event the head 14 and shank 16 are free to move apart and the valve door 2 may move from the main door.

The pin 13 may be integral with the head 14, if desired, and the threaded end of the shank may be reduced, as at 18 (see Fig. 3), to provide shoulders 19, which may seat against the back plate of the door to prevent shearing of the threads by inward pressure 25 established by movement of the valve door on the stud shank.

As shown in Fig. 4, the stud 20 may comprise a pin 21 in threaded engagement with the main door back plate 8 and extending in 35 to a recess 22 in the shank 23 which carries the head 24, there being solder 25 in the recess 22 which holds the pin 21 and shank 23 together until the solder fuses.

As shown in Fig. 5, the stud 26 may comprise a shank 27 which at one end is in 40 threaded engagement with the back plate 8, and which, at the other end, seats in a recess 28 in the head 29, there being solder 30 in the recess 28 holding the shank and head 45 together until the solder fuses.

The cheapness, simplicity and efficiency of the construction will be readily apparent. When the heat, conducted through the metallic studs, or otherwise, to the solder in the 50 studs fuses the solder, the springs 9 firmly seat the valve door against the jamb shoulders 11. Vapor pressure against the outside of the valve door, created by heat or fire, also serves to seat and hold the valve door 55 more firmly against these jamb shoulders. Thus there is established and maintained an effective seal across the safe doorway which will tend to prevent heat, fire, steam, or the like, from passing the valve door, and gaining access to the contents of the safe. The 60 valve door, being freed from restraint by the studs when the solder fuses, is maintained in sealing position irrespective of the warping or bulging of the main door, as 65 often occurs under the high temperatures of

a fire hazard. It will be apparent that the solder will fuse before the fire hazard has reached a great height, and thus the sealing of the doorway will be effected very quickly when a fire hazard arises, and the sealing 70 will not be delayed long enough to permit previous harm to the safe contents.

As many changes could be made in the above construction and many apparently widely different embodiments of this invention could be made without departing from the scope thereof, it is intended that all matter contained in the above description or shown in the accompanying drawings shall be interpreted as illustrative and not in a 80 limiting sense.

What I claim is:

1. In a door of the character described, in combination, a main door, a valve door, and means holding the valve door in place on 85 said main door and responsive to heat to release the valve door from the main door.

2. In a door of the character described, in combination, a main door, a valve door, and means holding the valve door in place on 90 said main door and responsive to heat to release the valve door from the main door, said means including readily fusible material substantially as described.

3. In a door of the character described, in combination, a main door, a valve door, and means holding the valve door in place on 95 said main door and responsive to heat to release the valve door from the main door, said means including two members normally 100 held together and adapted to come apart at a certain temperature, one member engaging the valve door and the other member engaging the main door.

4. In a door of the character described, 105 in combination, a valve door, a main door, and a stud including a portion engaging the main door and another portion engaging the valve door, and means, including 110 fusible material holding said stud portions together when the material is hard, and releasing said portions from each other when the material is fused, whereby said valve door is held to said main door when the fusible material is hard and is released therefrom when the material is fused.

5. In a door of the character described, 115 in combination, a valve door, a main door, and a stud including a portion engaging the main door and another portion engaging the valve door, and means, including fusible material holding said stud portions together 120 when the material is hard, and releasing said portions from each other when the material is fused, whereby said valve door is held to said main door when the fusible material is hard and is released therefrom when the material is fused, one of said stud portions having a recess and the other stud portion having a part seated in said recess, 125 130

the fusible material being in said recess and engaging the adjacent parts of both stud portions.

6. In a door of the character described, 5 in combination, a valve door, a main door, and a stud including a head portion engaging the valve door and another portion engaging the main door, said portions being soldered together by readily fusible material, substantially as described.

7. In a door of the character described, 10 in combination, a valve door, a main door, and a stud including a head portion engaging the valve door and another portion engaging the main door, said portions being soldered together by readily fusible material, said stud also including a shank portion extending through the valve door, and the valve door being movable on said shank, 15 substantially as described.

8. In a door of the character described, 20 in combination, a valve door, a main door, a stud including a head portion engaging the valve door and another portion engaging the main door, said portions being soldered together by readily fusible material, substantially as described, and a spring compressed between the valve door and the main door urging the doors to move apart.

25 9. In a door of the character described, in combination, a valve door, a main door, a stud including a head portion engaging the valve door and another portion engaging the main door, said portions being

soldered together by readily fusible material, substantially as described, and a spring compressed between the valve door and the main door urging the doors to move apart, the stud shank penetrating the spring, whereby the spring is held in place.

30 10. In a door of the character described, in combination, a main door, a valve door, and means holding the valve door in place on said main door and responsive to heat to release the valve door from the main door, 45 and means for moving the valve door away from the main door when released therefrom by the holding means.

11. In a door of the character described, 50 in combination, a main door, a valve door, and means holding the valve door in place on said main door and responsive to heat to release the valve door from the main door, a jamb portion having shoulders for the valve door, and means for seating the valve door, when released from the main door by said holding means, against said shoulders.

55 12. In a door of the character described, in combination, a main door, a valve door, 60 and means holding the valve door in place on said main door, for limited movement thereon, and responsive to heat to release the valve door from the main door.

This specification signed this 13th day of 65 September, 1924.

CARL P. BARTELS.
